UNITED STATES PATENT OFFICE.

FREDERICK W. KRAFFT, OF BERKELEY, CALIFORNIA.

WALL-PAPER CUTTER.

1,279,880.

Specification of Letters Patent. Patented Sept. 24, 1918.

Application filed April 27, 1917. Serial No. 164,983.

To all whom it may concern:

Be it known that I, FREDERICK W. KRAFFT, a citizen of the United States, residing at Berkeley, in the county of Alameda and State of California, have invented certain new and useful Improvements in Wall-Paper Cutters; and I do hereby declare the following to be a full, clear, and exact description of the invention, such as will enable others skilled in the art to which it appertains to make and use the same.

This invention relates to improvements in wall paper cutters.

The object of this invention is to provide a cutter especially adapted for trimming the edges of lengths of wall paper evenly and uniformly and is equipped with a novel roller and cutting means, whereby the edge of the paper after being cut will be prevented from rolling up or curling after it is cut.

Another object of this invention is to provide a wall paper cutter, which is equipped with novel means for clamping the same to a table so that the body of the cutter may be moved at various angles with relation to the table when cutting the lengths of paper in various configurations.

A further object of this invention is to provide a wall paper cutter which is adapted to cut off any length of paper and to cut across the paper dividing it in lengths as the paper is rolled out on the supporting frame.

A still further object of this invention is to provide a wall paper cutter which will cut off the bottom edges of the strips at the base-board when they are pasted on the wall, and a frame carrying the cutter to follow exactly after the cutter wheel to prevent tearing the paper by the frame, and the journaling of the cutter wheel or disk to the axle upon which the flat wheel is secured will cause the cutter to revolve and thus obviate sliding of the cutter and pulling and tearing of the paper.

A further object of this invention is to provide a spring which will normally hold the wheel down so that it will always revolve, and thereby prevent the disk from sliding and tearing the paper.

A further object of this invention is to provide a wall paper cutter, which includes a body, a frame embracing one edge of the body, a disk knife and roller supporting frame slidably mounted on the side edge of the first named frame, means connected to the second named frame for pulling the cut-

ter and roller to cut the lengths of paper and provide a straight and uniform edge.

A still further object of this invention is to provide a device of this character, which will be simple, durable and efficient, and which may be manufactured and sold at a comparatively low cost.

With these and other objects in view, the invention consists in the novel combination and arrangement of parts as will be herein-after more fully described and set forth in the claim hereto appended.

In the drawings:

Figure 1 is a side elevation illustrating the wall paper cutter applied to a table as made in accordance with this invention,

Fig. 2 is a top plan view of the same,

Fig. 3 is a longitudinal sectional view taken on the line 3—3 of Fig. 2,

Fig. 4 is a transverse sectional view illustrating the manner in which the frame for supporting the roller and knife is associated with the main or supporting frame,

Fig. 5 is a top plan view of the supporting frame adapted to be removably secured to one end of the first named frame to permit the first named frame to be moved in various angled positions with relation to the table,

Fig. 6 is a fragmentary sectional view taken on the line 6—6 of Fig. 3.

Like numerals of reference designate corresponding parts in all the figures of the drawings.

Referring more particularly to the drawings, the numeral 1 designates a table or other suitable support upon which my improved device is adapted to be applied.

My improved wall paper cutter comprises a supporting base 2, which is constructed of wood or any other suitable material and is substantially triangular in cross section and the base of the supporting body is provided adjacent its upper edge with the longitudinally extending cut out portion 3, which defines the shoulder 4, having the horizontal upper surface 5, the purpose of which will be hereinafter more fully described.

A metal plate 6 is secured to the upper face of the body 2 and extends longitudinally thereon and is rigidly secured thereto by suitable fastening means 7, such as rivets, screws or the like.

The forward edge of the plate 6 projects forwardly beyond the vertical wall of the

cut out portion 3 and is in a substantially horizontal plane as at 8. The horizontal portion overlying the cut out portion 3 is flush with the vertical wall 9 of the shoulder 4, thus defining a longitudinally extending groove, the purpose of which will hereinafter appear.

A substantially L-shaped metal guide plate 10 is secured by its horizontal flange 10 to the under side of the body 2 by suitable rivets, screws or the like designated 11. Thus its vertical flange 12 is arranged at a spaced distance from the vertical face 9 of the shoulder 4 of the body 2, thus defining 15 the longitudinally extending slot in which is slidably arranged the standard 13, which constitutes a frame.

The standard 13 extends vertically up through the slot defined by the guide plate 20 10 upwardly beyond the upper surface of the horizontal portion of the plate 6, and this standard is provided on its inner face adjacent its lower end with a laterally extending projection 14, which is substantially 25 rectangular in cross section and is adapted to be slidably arranged between the horizontal shoulder 5 and the under side of the horizontal portion 8 of the plate 6 and in the cut out portion 3 of the body 2.

30 The upper end of the standard is bent angularly in a horizontal plane as at 15, and has rigidly secured thereto, as at 16, a flat spring member 17, which spring member extends rearwardly and downwardly as at 35 18 and looped back upon itself as at 19 to provide the horizontal parallel upper bar 20, which bar extends forwardly beyond the standard 13. A substantially U-shaped member 21 is secured by its web to the under side 40 of the arm 20 as at 22, and has pivotally secured or journaled in the lower ends of its arms, the transverse shaft 23.

A roller 24 is rotatably mounted on the shaft 23 and is located between the arms of 45 the member 21. A cutting disk 25 of a diameter larger than the roller 24 is keyed or secured to the transverse shaft 23.

The peripheral edge of the disk defines a cutting edge 26, which is provided by the 50 beveling of the opposite side faces of the disk 25 outwardly. The roller 24 is keyed to the shaft 23 and has secured to one side, the disk 26 and the roller and disk are mounted upon the shaft for rotation therewith, thus it can be seen that upon movement of the frame in the slot, defined by the guide plate 10 and the cut out portion 3, that the disk and roller will be rotated.

The spring member 17 normally tends to 60 urge the roller into engagement with the upper side of the horizontal portion 8 of the plates 6, the purpose of which will be hereinafter more fully described.

A longitudinally extending handle member 65 27 is arranged to extend in the longi-

tudinally extending cut out portion 3 and has its inner end secured to the rectangular lateral projection 14 on the standard 13 as at 28 and its opposite end extends forwardly beyond the free end of the body 2 and terminates in a handle 29, facilitating the drawing of the cutter forwardly and forcing the same rearwardly after the operation of cutting the paper has been completed.

The body 2 is provided adjacent one end 75 centrally of its side edges with an opening 30 through which there is adapted to be removably arranged or fitted, a bolt 31, which has fitted on its lower end, a nut 32. A substantially V-shaped plate 33 is provided in 80 its apex with an opening 34. The plate is also provided with an arcuate slot 35, which slot is adapted to align with a transversely extending slot 36, located in the base 2 adjacent one end and centrally of the side edges 85 thereof.

A pair of U-shaped yokes 37 are secured by their webs to the under side of the plate 33 adjacent each end of the base thereof, the arms of the yokes curve upwardly and outwardly as at 38 and have pivotally secured therein, the clamping members 39, which members are eccentrically mounted in the arms 38 and are provided on their outer surfaces with the serrated surface 40, which 90 facilitates the clamping of the plate to the under side of a table, support or the like 1 as shown.

The plate 33 is secured to the under side 95 of the base 2 by the bolt 31 and nut 32, thus 100 pivotally securing the plate to the base member, and the base member and plate are rigidly secured to the support 1 by the clamping member 39.

A bolt having a shank 41 is provided at 105 one end with an annular flange 42, which has secured on its upper side the operating member 43, the outer end of the shank being provided with oppositely extending lateral projections 44, and the shank and projections are adapted to extend through the slot in the body 2 and through the arcuate slot 35 of the plate and turned for rigidly supporting the body 2 at various angled positions upon the surface of the table or support 1.

In operation, the device is clamped to a table as described, the paper is laid across the table and over the plate 6, the base 2 is then adjusted to compensate for the line of travel of the disk and roller, the handle 29 is grasped by the operator, the device is pulled toward him thus the disk cuts the paper leaving a straight edge or any desired edge required, and the roller engages the edge after it is cut, preventing the same from curling or wrinkling after being cut.

When it is desired after the paper has been cut, the handle is forced rearwardly placing the machine back to the opposite end 130

of the base in its initial position and it is ready for another operation.

What is claimed is:

A device of the class described including a base, a plate secured to the upper and lower sides of the base and terminating adjacent one end thereof, defining a vertical and longitudinal slot, a vertical standard 5 slidable in the vertical slot, a projection carried by the standard and slidably arranged in the longitudinal slot, a U-shaped knife supporting frame, a spring secured to the web of the frame by one end, a transverse shaft journaled in the arm of the frame, a 10 roller and disk knife secured to the shaft for rotation therewith, said disk being located to move in the vertical slot, means for connecting the free end of the spring to standard 15

for movement therewith, means for actuating the standard to move it in its respective slot, a plate pivotally secured to the base, clamps carried by the base to facilitate the securing of the same to a table or support, said plate provided with an arcuate slot coinciding with vertical slot in the base, and a thumb screw extending through the vertical slot and arcuate slot of the plate to permit the base to be adjusted at various angles with relation to the plate, as and for the purpose specified. 20 25 30

In testimony whereof I affix my signature in presence of two witnesses.

FREDERICK W. KRAFFT.
